INTERNAL-COMBUSTION ENGINE

Albert Collinson Nesfield, Ealing, London,
EnglandApplication February 18, 1944, Serial No. 522,865
In Great Britain January 19, 1943

13 Claims. (Cl. 123—65)

This invention relates to control of the flow of gases in internal combustion engines and more particularly to methods of and means for controlling the exhaust of internal combustion engines of the two-stroke cycle type.

In such engines it may be necessary or advisable to maintain a valve open to allow flow of gases for a very short period, for example, for a period comprising a small fraction of a second. Owing to the inertia of valve members it has hitherto been impracticable to provide a satisfactorily operating controllable valve for this purpose.

The invention will be described hereinafter with reference to its application to the control of the exhaust gases of an internal combustion engine of the two-stroke cycle type. In such engines the generally accepted theory of the conditions which exist after the explosion of a charge within a cylinder and the opening of the exhaust ports is that there is a first period (hereinafter termed "first period") wherein a mass or body of burnt gases is discharged from the cylinder at very high speed and on issuance sets up in the cylinder a high partial or almost complete vacuum. This body of burnt gases then undergoes a to and fro movement of high frequency out of and into the cylinder due to its impact with the gas mass in the exhaust conduit which produces within the cylinder alternate negative and positive pressure fluctuations. This period of pressure fluctuations is followed as the gases pass through the exhaust conduit by a second period of substantially continuous depression within the cylinder and this depression may be utilised, if an inlet valve is opened, to effect the recharging of the cylinder. This latter depression is, however, somewhat less than the first initial depression created during the first period above-mentioned and if the exhaust port can be closed immediately after the moment of primary ejection of the exhaust gases occurring in the above-mentioned first period the higher depression then set up can be utilised more advantageously to recharge the cylinder.

Since the time period during which the primary ejection of the exhaust gases in the so-called first period takes place may be of the order of 0.01 to 0.001 second after the opening of the exhaust ports it is substantially impossible to open and to close said ports within such a short period owing to valve inertia. The present invention may be applied to control the flow of exhaust gases so that the exhaust period is of the relatively small duration above-mentioned.

One object of the present invention is to provide an operative cycle for two-stroke cycle engines which utilises the depression of the above-mentioned first period for cylinder charging purposes.

Another object of the invention is to provide an improved valve arrangement adapted to effect exhaust cut-off within the time limits of 0.01 to 0.001 second after opening of the exhaust valve or port.

A further object of the invention is to provide means for readily varying the moment of exhaust cut-off in two-stroke cycle engines, if desired, automatically in accordance with the engine speed.

In connection with engines of the type hereinbefore referred to suggestions have been made to interpose a one-way acting flap valve in the exhaust conduit which shuts immediately on reduction of pressure within the cylinder and prevents the return flow of exhaust gases into the cylinder after the first period of exhaust. Such valves are, however, impracticable in continuous operation and are not positively controllable.

Other proposals have been to include positively driven rotary valves in the exhaust conduit in cases where the second period of exhaust is being utilised for cylinder charging purposes.

The term "main exhaust port" herein used is intended to include a port or ports in the cylinder wall covered and uncovered by the reciprocating piston itself or by a sleeve valve or ports controlled by an external piston valve or by a rotary valve or by a valve of the poppet type.

Further objects and advantages of my invention will be apparent from the following description considered in conjunction with the accompanying drawings which form a part of this specification and of which—

Fig. 1 shows diagrammatically the application of the invention to an internal combustion engine cylinder having its ports controlled by a reciprocating piston;

Fig. 2 shows in vertical section an internal combustion engine incorporating the valve element according to the invention;

Fig. 3 is a section on the line III—III of Fig. 2 through the exhaust valve cam shaft transmission;

Fig. 4 shows a speed responsive governor applied to the arrangement of Fig. 3; and

Fig. 5 is a diagram showing the moments of opening and closing of the valves in the improved two-stroke cycle.

Referring to the drawings, Fig. 1 shows dia-

grammatically an engine cylinder 10 containing a reciprocating piston 11, a series of exhaust ports 12 and a series of inlet ports 13. The exhaust ports 12 communicate with an exhaust conduit 14 and the inlet ports 13 communicate with an admission conduit 15.

Located within exhaust conduit 14 adjacent the ports 12 is a valve 16 of the poppet type which is controlled as to its closing movement by means of a spring 17 and opened by means of a rocker arm 18 pivoted at 19 and controlled by a cam 20. The cam 20 may, for example, be of the spiral type having a substantially radial face 21 to allow rapid closing of the valve under the influence of the spring 17. To reduce friction a roller 22 is preferably mounted on the arm 18 so as to contact with the face of the cam 20.

In operation, after the explosion of the charge within the cylinder 10 with the piston 11 moving downwardly within the cylinder as shown in Fig. 1, the valve 16 is first opened so as to provide a free passage for exhaust gases when the piston 11 later uncovers the ports 12. At a predetermined moment after the opening of the exhaust ports 12 the poppet valve 16 is closed by spring action owing to the face 21 of the cam rotating opposite the roller 22 and substantially at the same instant the piston 11 in its continued downward movement uncovers the inlet ports 13.

The moment of closing of the poppet valve 16 is approximately at the instant of termination of the so-called first period of exhaust, at which moment the body of exhaust gases has been ejected from the cylinder, leaving within the cylinder a very high depression. The closing of the exhaust valve 16 prevents any return surge of gases passing back through that portion of the exhaust conduit denoted by 23 from entering the cylinder and maintains the depression within the cylinder, which at the moment of opening of the inlet ports 13 is automatically recharged by the inrush of the explosive charge through the admission conduit 15. On the closure of the inlet ports 13 at a suitable moment by means of the piston 11 on its upward compression stroke, the charge within the cylinder 10, due to its high velocity of entry, may be at a pressure above atmospheric.

Fig. 2 shows in vertical section a practical embodiment of the invention. As shown the cylinder 10 containing the piston 11 includes an exhaust port or ports 12, an exhaust conduit 14, an auxiliary poppet valve 16, a spring 17, a rocker arm 18 and cam 20. In this embodiment an inlet port 30 in the cylinder head is controlled by an inlet valve 31 controlled as to closing by a spring 32 and opened by means of a rocker arm 33 pivoted about a pin 34 and actuated at its opposite end 35 through a transmission rod 36 by a cam 37 mounted on a cam shaft 78 and rotated through suitable gear transmission (not shown) from a gear 38 mounted on the crank shaft 39.

The cam 20 is mounted on a cam shaft 40 which carries a pinion 41 meshing with an idler gear 42, in turn meshing with the gear 38 mounted on the crank shaft. The arrangement of these gears is shown more particularly in Fig. 3.

Since the moment of closing of the exhaust poppet valve 16 is of fundamental importance means are provided for adjusting the said moment of closing by adjustment of the angular setting of the cam shaft 40 and cam 20. This device is illustrated in Fig. 3 and shows the crank shaft gear 38 meshing with the idler gear 42 mounted by suitable ball bearings 43 on a stub

shaft 44; idler gear 42 in turn meshes with the pinion 41 mounted on the cam shaft 40.

The device for adjusting the angular setting of the cam shaft 40 comprises a bush 44 rotatable with the pinion 41 by key connections 45 and also slidable axially relative to the pinion 41. The bush 44 carries on its inner periphery a pin (not visible in Fig. 3) which engages within a helical groove 46 formed in the outer peripheral surface of the reduced end 47 of the cam shaft 40. The arrangement is such that axial movement of the bush 44 varies the angular setting of the cam shaft 40 relatively to the pinion 41 and thus relatively to the crank shaft 39 due to the interengagement of the pin on the inner face of the bush with the helical groove 46.

To effect this axial movement of the bush 44 there is provided in the embodiment of Fig. 3 a manipulating head 48 mounted on a rotatable spindle 49 carried by a suitable member of the apparatus casing. The outer surface of the spindle 49 is provided with threads and carries a collar 50 internally threaded to engage the spindle 49 but prevented from rotation by pins 51 on the collar engaging in a forked member 52 which pivots about a pin 53. The lower end 54 of member 52, also forked, engages in a groove 55 formed in the bush 44. By this means it is clear that rotation of the manipulating head 48 causes axial movement of the collar 50, which axial movement is transferred through the member 52, 54 pivoting about the pin 53 to the bush 44.

The provision of this manual adjustment enables an extremely fine variation of the setting of the cam 20 and thus a very fine variation of the moment of closing of the auxiliary poppet valve 16. This adjustment will normally take place while the engine is running so that the setting of the cam 20 may be varied to suit the particular characteristics of the individual engine.

Since obviously the timing of the opening of the exhaust valve will vary with variations in the speed of the engine, it is preferable to provide an automatic control responsive to the speed of the engine instead of the manual adjustable member 48 above-mentioned. Such a device is shown in Fig. 4 wherein the pinion 41 driving the cam shaft 40 through the bush 44 and helical groove 46, as described with reference to Fig. 3, meshes with a gear 60 forming part of a speed responsive governor denoted generally by 61. Governor 61 comprises a plate 62 of curved form and a further plate 63 mounted for free rotation on a stub shaft 64. The governor 61, 62 carries a number of, in the illustrated embodiment six, balls 65 mounted in radially directed grooves in the plate 63 which is urged by a spring 66 towards the plate 62 so as to maintain the balls in contact with said plate 62. A lever 67 pivoting about a pin 68 has a forked end 69 engaging a groove 70 formed in a boss on the rear face of the plate 63 and is provided with a projection 71 which engages within the groove 55 of the bush 44.

In operation of this device variation in engine speeds causes the radial position of the balls 65 to vary and through the curved face of the plate 62 sets up axial displacement of the plate 63 and through the lever 67 and projection 71 moves the bush 44 axially in response to the engine speed. Adjustment of the position of the axially movable bush 44 varies the angular displacement of the cam shaft 40 relatively to the crank shaft according to the speed of the engine. This in turn determines the moment of closing of the exhaust

poppet valve 16, thus obtaining maximum efficiency of operation over a wide range of engine speed.

Since the cam shaft 18 carrying the cam 37 is preferably driven from the gear 38 mounted on the crank shaft in the same way as the cam shaft 40, a regulating device as described with reference to Fig. 3 or Fig. 4, may, if desired, be interposed between the cam shaft 18 and the gear transmission effecting the drive from the pinion 38 mounted on the crank shaft. In this way the moment of opening and closing of the inlet valve may be controlled so as to provide accurate timing of said valve movement.

Fig. 5 indicates diagrammatically the operative cycle of the two-stroke cycle combustion engines hereinbefore described. Fig. 5 shows the moments of opening and closing of the exhaust and inlet valves with respect to crank shaft rotation. For example, the exhaust ports 12 may be opened at the point A in Fig. 5, approximately 120° after the top dead centre of the crank. The exhaust takes place during a period corresponding to a further crank rotation of approximately 30°, at which point the auxiliary poppet valve 16 is closed as indicated by the point B. Substantially at this moment the inlet valve 31 (Fig. 2) is opened and the inlet valve is again closed when the crank shaft has reached its bottom dead centre position as indicated by the point C in Fig. 5. The inlet valve thus remains open during rotation of the crank shaft through about 30° but there may be a slight overlap in the periods during which the exhaust poppet valve 12 and the inlet valve 31 are open. That is to say, the inlet valve may for example, be opened during the last 5° of crank shaft rotation, during which the exhaust poppet valve 16 remains open. In any case the inlet valve is not opened until the outflow of exhaust gases from the cylinder during the so-called first period of exhaust has substantially ceased.

While I have described and illustrated several embodiments of my invention it is to be understood that this is for the purpose of illustration only and that the scope of my invention is not to be limited thereby but is to be determined by the appended claims.

What I claim is:

1. That improvement in the operative cycle of an internal combustion engine of the two-stroke cycle type which consists in controlling the commencement of the exhaust period by means of the normal exhaust ports, terminating the exhaust period substantially instantaneously by means of an auxiliary cam actuated spring loaded valve and opening an inlet valve substantially at the moment of closing of said auxiliary valve, when the flow of exhaust gases from the cylinder at the end of the so-called first period of exhaust has substantially ceased.

2. In an internal combustion engine of the two-stroke cycle type having an exhaust conduit and a main exhaust port providing communication between the engine cylinder and said conduit, the method of controlling the outflow of exhaust gases which consists in opening a positively spring actuated auxiliary valve located in said exhaust conduit adjacent the main exhaust port after the explosion of the charge, subsequently opening said main exhaust port to allow ejection of burnt gases into said exhaust conduit and closing said auxiliary valve at the termination of the so-called first period of exhaust to

prevent a return surge of gases into the cylinder through said main exhaust port.

3. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, means to open said auxiliary poppet valve operative prior to the opening of said main exhaust port, means to close said auxiliary poppet valve to cut off communication between said exhaust conduit and said cylinder and means responsive to the engine speed to vary the moment of closing of said poppet valve.

4. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, means to open said auxiliary poppet valve operative prior to the opening of said main exhaust port, means to close said auxiliary poppet valve to cut off communication between said exhaust conduit and said cylinder, an inlet valve and means to open said inlet valve substantially at the moment of closing of said poppet valve.

5. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, a rotating shaft, a cam shaft having a helical groove therein, a cam mounted on said shaft and positively controlling the movement of said poppet valve, transmission means driving said cam shaft from said rotating shaft, a bush rotatable with and slidable axially relatively to said transmission means, a pin on said bush engaging in said helical groove and means to produce axial movement of said bush and thereby to vary the angular setting of said cam shaft and said cam.

6. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, a rotating shaft, a cam shaft having a helical groove therein, a cam mounted on said shaft and positively controlling the movement of said poppet valve, transmission means driving said cam shaft from said rotating shaft, a bush rotatable with and slidable axially relatively to said transmission means, a pin on said bush engaging in said helical groove and means responsive to the engine speed to produce axial movement of said bush and thereby to vary the angular setting of said cam shaft and said cam according to the speed of the engine.

7. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main

exhaust port, a rotating shaft, a cam shaft having a helical groove therein, a cam mounted on said shaft and positively controlling the movement of said poppet valve, transmission means driving said cam shaft from said rotating shaft, a bush rotatable with and slideable axially relatively to said transmission means, a pin on said bush engaging in said helical groove, means to produce axial movement of said bush and thereby to vary the angular setting of said cam shaft and said cam, an inlet valve and means to open said inlet valve substantially at the moment of closing of said poppet valve.

8. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, a rotating shaft, a cam shaft having a helical groove therein, a cam mounted on said shaft and positively controlling the movement of said poppet valve, transmission means driving said cam shaft from said rotating shaft, a bush rotatable with and slideable axially relatively to said transmission means, a pin on said bush engaging in said helical groove, means responsive to the engine speed to produce axial movement of said bush and thereby to vary the angular setting of said cam shaft and said cam according to the speed of the engine, an inlet valve and means to open said inlet valve substantially at the moment of closing of said poppet valve.

9. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, a rotating shaft, a cam shaft having a helical groove therein, a cam mounted on said shaft and positively controlling the movement of said poppet valve, transmission means driving said cam shaft from said rotating shaft, a bush rotatable with and slideable axially relatively to said transmission means, a pin on said bush engaging in said helical groove, means to produce axial movement of said bush and thereby to vary the angular setting of said cam shaft and said cam, an inlet valve, means to open said inlet valve substantially at the moment

of closing of said poppet valve, and means to vary the moment of opening of said inlet valve.

10. An internal combustion engine of the two-stroke cycle type having a cylinder and an exhaust conduit which includes a main exhaust port controlling communication between said cylinder and said exhaust conduit, an auxiliary poppet valve located in said exhaust conduit adjacent said main exhaust port, means to open said main exhaust port, a rotating shaft, a cam shaft having a helical groove therein, a cam mounted on said shaft and positively controlling the movement of said poppet valve, transmission means driving said cam shaft from said rotating shaft, a bush rotatable with and slideable axially relatively to said transmission means, a pin on said bush engaging in said helical groove and a speed responsive governor producing axial movement of said bush and thereby varying the angular setting of said cam shaft and said cam.

11. That improvement in the operative cycle of an internal combustion engine of the two-stroke cycle type which consists in controlling the commencement of the exhaust period by means of the normal exhaust ports, terminating the exhaust period by means of an auxiliary spring controlled valve and opening an inlet valve substantially at the moment of closing of said auxiliary valve, when the flow of exhaust gases from the cylinder at the end of the so-called first period of exhaust has substantially ceased.

12. An internal combustion engine of the two-stroke cycle type which includes a main exhaust port and an auxiliary spring-actuated valve arranged in series in the path of flow of the exhaust gases and cam means cooperating with said actuating spring to provide approximate instantaneous closing of said auxiliary valve by said spring substantially at the instant of termination of the so-called first period of exhaust.

13. An internal combustion engine of the two-stroke cycle type which includes a main exhaust port and an auxiliary spring-actuated valve arranged in series in the path of flow of the exhaust gases, cam means cooperating with said actuating spring to provide approximate instantaneous closing of said auxiliary valve by said spring substantially at the instant of termination of the so-called first period of exhaust and means for varying the moment of closing of said auxiliary valve.

ALBERT COLLINSON NESFIELD.
